UNITED STATES PATENT OFFICE.

GEORGE L. BENNETT, OF CLEVELAND HEIGHTS, OHIO.

ICE-VENDING MACHINE.

Application filed July 12, 1924. Serial No. 725,754.

- My invention relates to ice vending machines and more particularly to a machine adapted to have stored therein large cakes of ice, and having mechanisms by which these cakes will be automatically fed in relation to a delivery mechanism and a cutoff mechanism for separating each cake into a plurality of smaller pieces of substantially uniform bulk.
- 10 The machine of my invention is designed for use as an ice station from which the purchasing public may obtain ice at retail without requiring the services of an attendant, the machine being automatic in all of its functionings excepting the charging of the storage chamber with the large cakes of ice, and the starting of the machine and the removal of the piece of ice which result from the acts of the purchaser.
- 20 In the machine of my invention, there is no definite limitation upon the storage capacity, and the labor cost of operation is limited to that incidental to the delivery of large cakes of ice to the machine and the collection of the coins or checks deposited in the machine with incidental inspection to ensure the maintenance of an adequate supply of ice at all times.
- 25 The machine is capable of operation at a speed at least commensurate with the handling of the ice by the purchaser, the delivery of the ice following the deposit of a coin or check in the machine with sufficient rapidity to avoid unnecessary delays from this source.
- 30 The mechanisms in the machine are such that the large cakes of ice are delivered and progressively advanced in relation to a cutoff mechanism, it being possible and preferable to so construct the feeding mechanism for the cake of ice as to compensate for the varied dimensions throughout the cake, and cause each piece of ice served from the cake, to be of substantially the same bulk and weight as every other piece. The loss from shrinkage is reduced to minimum since the whole mechanism may be contained within a suitably insulated housing, maintained at a temperature sufficiently low to prevent any material melting of the ice by means other than the ice stored in the machine for sales purposes.
- 35 The mechanism for delivering the cakes of ice from the storage compartment to the feeding mechanism, is so constructed that the different cakes of ice will be spaced apart sufficiently to avoid their binding together, thus permitting the handling and delivering of clean ice.
- 40 The mechanism used for separating the cakes of ice into smaller pieces is such as to avoid any material chipping or breaking of the ice, the delivery mechanism also being so constructed that each piece of ice will be delivered in good condition to the purchaser, and the presence of small particles of ice in and about the delivery mechanism tending to interfere with the actuation of this mechanism, will be avoided entirely or reduced to a minimum.
- 45 In order to ensure the proper intermittent feeding movement of the cake of ice in relation to the cutoff mechanism, I provide a feeding mechanism with controlling means so constructed and arranged as to ensure the ice being advanced with relation to the cutting mechanism only as such movement is required, and to limit this movement to a distance required to cause a delivery of a piece of ice upon a succeeding operation of the machine of the desired bulk and weight.
- 50 I embody in the machine various refinements for ensuring the maintenance of the ice in the proper position as it is being fed in relation to the cutoff mechanism and to cause the actuation of the feeding mechanism in a manner to bring a fresh cake of ice within the operative range of the feeding mechanism before the complete exhaustion of the preceding cake, thus ensuring the delivery of a piece of ice with the deposit of each coin, and avoiding all disturbances and loss through a failure of the machine to thus operate.
- 55 The invention consists primarily in an ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, a storage mechanism adapted to deliver cakes of ice as required in operative relation to said feeding mechanism, delivery means whereby pieces of ice severed by said cutoff mechanism from the cakes of ice are delivered exteriorly of the machine, means whereby the operation of said mechanisms may be controlled exteriorly of the machine,

and an insulated housing inclosing said mechanisms; and in such other novel features of construction and combination of parts as are hereinafter set forth and described, and more particularly pointed out in the claims hereto appended.

Referring to the drawings,

Fig. 1 is a transverse vertical section through the mechanisms of the machine; 10 Fig. 2 is a plan view of the mechanisms shown in Fig. 1 showing a portion of the storage mechanism;

Fig. 3 is a longitudinal condensed sectional view from the left of Fig. 1.

15 Fig. 4 is a detail view of the actuating means for the cutoff mechanism, for the delivery mechanism and for the control for the feeding mechanism; and

Fig. 5 is a diagrammatic view showing 20 the wiring for controlling the operation of the feeding mechanism.

Like numerals refer to like parts throughout the several views.

In the embodiment of my invention shown 25 in the drawings, the operative mechanisms of the machine are enclosed by a house 10 having heat insulated walls and provided with suitable bunkers for the reception of broken or waste ice and salt, for the purpose 30 of bringing, and maintaining, the interior of the house to and at substantially the freezing point of water for the purpose of preventing wastage by melting, of the cakes of ice to be merchandised, and also the formation 35 of a moisture film upon these cakes of ice which might tend to cause the cakes to adhere to mechanisms in the machine or to each other, in the event that it is not found expedient to employ the form of storage 40 mechanism particularly referred to herein-after.

The house 10 has a suitable door 11 therein, by means of which the storage chamber may be charged and recharged with cakes 45 of ice, it being preferable to provide a platform 12 adjacent said door, and of a height to receive cakes of ice from a wagon.

Within the house 10 are the mechanisms by 50 which a cake of ice may be automatically cut into a plurality of pieces of substantially uniform weight and bulk, which I have termed a cutoff mechanism, a mechanism by which each cake of ice is intermittently fed in relation to said cutoff mechanism, a delivery mechanism adapted to receive pieces of ice, one piece at a time, after it has been cut from the cake; a storage mechanism adapted to receive a number of cakes of ice and to automatically deliver them to the 55 feeding mechanism as required, and a check controlled mechanism adjacent the delivery mechanism so that the various mechanisms within the house 10 may be controlled by a 60 purchaser, but will, in all other respects, be 65 automatic in their functionings.

Within the housing 10 is a slideway 13 which may be made of any desired material, or of any desired construction to facilitate the movement of a cake of ice along same by the feeding mechanism.

70 Adjacent one end, at opposite sides of, and above this slideway are oppositely disposed, vertically arranged rows of picks or chisels, 14-15, movable toward and from each other. These picks or chisels are carried respectively upon suitable bars 16 and 17 mounted upon wheeled carriages such as 18, see Fig. 3, although the supports 16 and 17 for said picks may be mounted to have movement by any means other than the carriage as shown.

75 Adjacent each of the supports 16 and 17 is a fixed vertical standard 19-20 each connected with its support by a series of toggle levers 21-22, for imparting movement to the support and the picks or chisels, through a mechanism operative thereon.

80 Hinged to each of the supports 16 and 17 is a bar 23-24 extending at right angles thereto, and each carrying a line of horizontally disposed picks or chisels 25 and 26. The picks or chisels 25 and 26 are positioned substantially coincident with the center line of the cake of ice, so that with each actuation 85 of the cutoff mechanism a portion of the end of a cake will be split therefrom by the lines of picks 14 and 15, and the piece thus split from the rest of the cake will be cut in half horizontally by the picks or chisels 25 and 26.

85 Each set of toggle levers 23-24 is acted 100 upon by a restoring spring 27-28.

Connected with the toggle levers of each set is a thrust bar 29-30, acting against the tension of the springs 27 and 28, under the control of a cutoff cam 31-32, each cam 105 corresponding in construction and setting to the other.

The said cams are actuated by a motor 33 connected with a shaft carrying said cams by a speed reducing gearing 34.

110 Each of the cams 31 and 32 has a sequence of short risers thereon, of progressively increasing heights, shown more particularly in Figs. 1 and 4, at 35, a concentric portion 36 of substantially the same radius as the highest one of the risers 35, and extending in arc a sufficient distance to hold the picks in their innermost position for a sufficient interval to permit the delivery of the upper piece of ice during the actuation of the 115 hinged bars 23 and 24, just prior to the cam coming to rest after a movement of 180° in arc. Beyond the concentric portion 36 is a single riser 37, and a gradual fall 38, to the shortest radius of the cam, this construction being to give one actuation to the picks or chisels upon the succeeding actuation of the machine followed by a complete withdrawal of the chisels, to permit the delivery 120 of the lower piece of ice.

The movement of the cam is divided during each rotation, into two stages, each 180° in arc, the risers 35 and portion 36 being operative during the first stage, and the 5 riser 37 and fall 38 being operative during the second stage.

Leading from adjacent the end of the slideway 13 is a delivery chute 39 forming a part of the delivery mechanism, this chute 10 passing through the walls of the house 10 to a delivery chamber at 40 adjacent the check controlled mechanism, to be referred to hereinafter. There is arranged in the 15 length of this chute, a self-closing door 41 so that a piece of ice sliding down said chute will automatically open said door when passing to said receiving chamber, the door immediately closing to prevent the entrance of heated air into the house 10. Beyond the 20 end of this chute is a tilting bin 42 having one wall 43 normally closing the delivery opening adjacent the check controlled mechanism, and a wall 44 having a segmental shield 45 below same, adjacent the end of 25 the discharge chute. The bin is pivoted at 46 and is actuated by means of the links 47 controlled by a foot pedal 48.

Above the chute 39, and on substantially the same plane as the line of horizontal 30 picks 25 and 26 is a hinged chute section 49 supported by a counterweight 50, the chain of which passes over sheaves upon a shaft 51, which shaft is connected by means of the 35 gears 52 with a resistance device 53. Supported beyond the end of the supplemental chute 49 is a stop 54 having a bumper surface 55 presented toward the cutoff mechanism. This supplemental chute 49 is used only when delivering the upper piece of ice, 40 it being spaced away from the chute 39 sufficiently to afford the necessary clearance for the passage of the lower pieces of ice beneath same.

The ice is delivered to the chute section 45 49 through the tilting of the horizontal row of picks or chisels 25 and 26 by means of links 56 connected with the bars 23 and 24 and also with cranks 57 supported adjacent the cams 31 and 32 respectively and in 50 the path of movement of striker members 58 carried by the shaft of said cams. The cranks of said lever engage stops 59 and 60 which accurately position the hinged bars 23 and 24 and the picks or chisels 25 and 26 carried thereby. The striker members 58 are so set with relation to the cams 31 and 32 that they will engage and actuate the cranks 57, while the segment 36 of said fitting is in operative relation to the push 55 bars 29 and 30 respectively.

The construction of the feeding mechanism is such that a cake of ice 61 when deposited upon the slideway 13 will be acted upon following each complete rotation of the 65 cams 31 and 32, while the low point of the

fall 38 is engaging the push rods 29 and 30, and advanced toward, and into operative relation to, the cutoff mechanism, incidentally delivering the previously cut lower piece of ice. 70

This mechanism includes therein a carriage 62 movable along the slideway 13 under the control of a lead screw 63 and a co-operating traveller nut 64 upon the carriage. The lead screw 63 is driven from the 75 electric motor 65, the power to said motor being controlled by a make and break mechanism 67 upon the carriage adapted to be engaged and actuated, by a sequence of projections 68, 69, 70, 71, 72, 73 and 74 positioned at predetermined distances along the 80 slideway 13 so that the feeding movement of the carriage with each actuation of the motor 65 will be automatically stopped as a result of the interruption of the current by 85 the engagement of the make and break mechanism 67 with some projections 68 to 74. It will be readily understood that said projections 68 to 74 may be varied in number and in position to correspond with the 90 number of vertical cuts to be made upon each cake of ice and the spacing of these cuts.

The carriage 62 is provided with chucks 75 adjacent a bumper 76, these chucks being so formed as to compensate for the taper of 95 the ice cake, and bring the longitudinal center of the cake in substantial alignment with the horizontal rows of picks or chisels 25 and 26. Said chucks slide along the slideway 13 and support the ice until after the 100 last vertical cut has been made in the cake of ice and the carriage is reversed or backed up to receive the succeeding cake of ice, the movement of which will upon that actuation of the machine deliver the last lower piece 105 of ice into which any cake is cut.

Since the carriage 62 advances by an intermittent movement toward the cutoff mechanism, but is moved in the reverse direction or backed up for the full length of 110 the slideway 13, when a fresh cake of ice is to be delivered to said slideway, it is apparent that the motor 65 must be a reversible motor, and the electrical controlling mechanism for this motor must be so arranged as 115 to reverse the current thereto when the functioning of the machine so requires.

To secure this result I provide in circuit with the switch mechanism 67, a pole changing switch 77 having an actuating member 120 78, adapted to be engaged by abutments 79 and 80 adjacent opposite ends of the slideway 13.

Upon the carriage 62 are upper and lower automatically actuated tongs, the jaws of 125 which are positioned upon both sides of the slideway so as to steady a cake of ice 61 while it is upon the slideway. The upper tong jaws are shown at 81 and 82 and the lower tong jaws at 83 and 84. 130

Each jaw is separately pivoted, and has two arms 85 and 86, one of which 85 is adapted to be engaged by studs 87 and 88 adjacent the cutoff mechanism, and the other 5 of which 86 is adapted to be engaged by studs 89 and 90 adjacent the end of the slideway toward the motor 65. The jaws are acted upon by springs 91 and 92 which will automatically close them, the studs 89 and 90 preventing these springs acting while the cake of ice is being delivered to the slideway. A stop member 93 is engaged by the arms 86 and limits the opening movement of said jaws against the tension of said springs.

15 Carried by the bars 16 and 17 below the horizontal rows of picks 25 and 26 and between the end of the slideway 13 and the adjacent end of the chute 39 are stops 94 and 95 which, while the segments 36 are in engagement with the push bars 29 and 30, will prevent the accidental escape of the lower piece of ice from the slideway onto said chute.

20 The storage mechanism in the machine includes therein a conveyor consisting of an endless belt 96 having thereon spacing blocks, or cleats, 97, and passing about rollers 98 and 99. The belt 96 is supported intermediate said rollers by suitable means 25 such as the rollers 100. The belt is arranged on an incline so that the weight of ice cakes deposited thereon will tend to impart the necessary movement to the belt to cause the ice cakes to be successively delivered therefrom onto skids 101 directed downwardly toward the slideway 13.

25 To ensure the proper timing in the actuation of said belt, I provide a braking mechanism or other means which is normally set 30 to prevent movement of the belt. The braking mechanism or other means is set by the weight of the cakes of ice upon the conveyor and is automatically released as a result of the movement of the carriage 62, in a manner to permit the delivery of one cake of 35 ice by the conveyor mechanism to the slideway, the succeeding cake of ice resetting the brake mechanism or other means, thus limiting the operative effect of the conveyor 40 mechanism to the delivery of one cake of ice at a time.

45 In the form of the invention shown, this controlling means for the storage conveyor consists of a brake drum 102 acted upon by a band brake 103, the actuating means for which consists of a lever 104 having secured thereto by a horizontal pivot, a controlling arm 105 adapted to project in the path of movement of ice upon the conveyor belt 96. 50 Mounted adjacent and below the controlling arm 105 is a shaft 106 carrying thereon a lift member 106^a in engaging relation with said arm 105, and a crank 107 in the path of movement of a striker member 108 upon the 55 carriage 62.

While the foregoing mechanisms are automatic in their functioning, it is to be understood that the delivery of pieces of ice is not continuous so that means must be provided readily accessible to the purchasing public, 70 whereby the operation of these mechanisms may be controlled so far as the initial application of power to the machine is concerned. Hence it will be readily understood that when the terms automatic and intermittent 75 are employed, such terms must be understood as defining definite cycles of the mechanism which are completed following a mere starting impulse and requiring a separate impulse for each cycle. It will also be 80 readily understood that different cycles of operation of the mechanisms are not the same, but will vary according to the conditions within the machine, and irrespective of any act of a purchaser.

85 The means for controlling the operation of the various mechanisms in the machine may take a variety of different forms, and include various arrangements of electrical switches, the following feature however, will 90 be, common to all arrangements which may be adopted, to wit:—the use of a circuit closing device which may be operated by the purchaser either by the deposit of a coin or check, or the use of a key; a make and break 95 mechanism actuated as a result of the rotation of the cams of the cutoff mechanism; a make and break mechanism for interrupting the circuit at predetermined intervals so as to control the feeding movements of the 100 carriage 62; a make and break mechanism for reversing the motor 65, these two last mechanisms being carried by and movable with the carriage 62, and a make and break mechanism also actuated as a result of the 105 movements of the cams of the cutoff mechanism, arranged in circuit with the two make and break mechanisms upon the carriage for ensuring a timely restarting of the carriage.

110 The functioning of all the make and break mechanisms excepting that controlled as a result of the deposit of a coin or check, or the use of a key in the machine, is entirely automatic.

115 In actual practice, the conditions within the house 10 are such as to make it desirable to use mercury switches, commonly known as mercoid switches, since, in this type of switch, the electrical contacts are immune 120 to deterioration as a result of moisture conditions within the house. In Fig. 5, I have illustrated diagrammatically an arrangement showing the use of switches of this type, although it is apparent that other types of make and break mechanisms may be employed in lieu thereof and secure the same operative effects, if not the same immunity 125 from likelihood of failure of the switches to operate.

130 Adverting first to the check or key con-

trolled make and break mechanism, this mechanism consists of a tiltable two-way switch member 109, the movements of which are controlled by mechanisms which form no part of the present invention, but may be of any old or well known construction. This mechanism controls the movement of a rock lever 110, operative upon said switch, and having actuating plungers 111 and 112 exposed exteriorly of the machine. One set of terminals of said two-way tilting member 109 is connected with the motor 33 through a similar switch mechanism 113 mounted adjacent the shaft 66 for the cams 31 and 32, which shaft also actuates a make and break mechanism controlling the circuit to the make and break mechanism 67.

The actuating means for the make and break mechanism 113 consists of a rock lever 114 mounted adjacent a cam 115 on the shaft 66 having a rise 116 and fall 117 each extending for substantially 180°, one end of said lever 114 being so acted upon by a spring as to be constantly engaged with said cam to limit the oscillatory movement of the lever and of the make and break mechanism 113 to that required, while ensuring the succeeding movements of said switch interrupting the circuit to the motor 33 following each 180° of movement of the cams 31 and 32, and positioning the member 113 so that upon the next actuation of the switch 109, the circuit will be closed to said motor 33.

Adverting to the make and break mechanisms controlling the movements of the carriage 62, the mechanism 67 is of the same type as the mechanisms 109 and 113, and is actuated by a rock shaft 118 having arms 119 and 120 adapted to engage the projections 68 to 74, the position of alternate projections being such that one projection will engage one of these arms, and the next will engage the other arm. The last projection 74 adjacent the cutoff mechanism will be so set that during the return movement of the carriage, neither arm 119 or 120 will engage any projection, a supplemental projection 68a being provided adjacent the end of the slideway 13 towards the motor 65 for the purpose of restoring said arms 119 and 120 to a position where, during the feeding movement of the carriage, they will engage the projections 68 to 74. The various switch mechanisms used throughout the device are of a well known type of construction more particularly described hereinafter.

The mechanism 67 is a two-way mercury switch always having one set of contacts closed, and the flow of the current to the motor 65 through this switch is controlled by a make and break mechanism 121, actuated from the shaft 66 of the cams 31 and 32. This mechanism 121 includes a two-way, tiltable mercury, or other similar, switch of the

same type as in the other make and break mechanisms described, one set of contacts of this switch being connected with one set of contacts upon the switch member 67, and the other set of contacts of said mechanism 121 being connected with the other set of contacts of the member 67. The members 67 and 121 are so set and so wired that movement of the member 67 will break the circuit in the motor 65, and movement of the member 121 will make the circuit to said motor.

The member 121 is actuated by means of a lever 122 co-operating with a cam 123 driven by a gear 126 carried upon a shaft counter to the shaft 66, and having a rise 125 and a fall 125a each extending for substantially 180°.

The lever 122 is so acted upon by a spring as to be constantly engaged with said cam 123 so as to cause the actuation of said make and break mechanism twice during each rotation of said cam but only once during each rotation of the shaft 66.

The gear 126 is connected to the shaft 66 by a small gear 124, the ratio of the gears 126 and 124 being as two to one, so as to cause the actuation of the member 121 once during each alternative rotation of the cams 31 and 32.

The make and break mechanism 77 is similar in construction to the mechanisms 109, 113 and 67, being tilted in opposite directions by the actuating member 78 and abutments 79 and 80 as heretofore described.

In a system of remote control operative automatically, the arrangement above described will be found highly satisfactory since the mechanisms 121 and 67 will always have one set of contacts closed, and the other set open, so that the movements of the carriage may be controlled as a result of a predetermined position of one of these switches with relation to the other, and thus permit the carriage to be stopped by the actuation of the mechanism 67, and started by the actuation of the mechanism 121.

Arranged in circuit with the switches 113, 67 and 77 is what may be termed a loading switch, the purpose of which is to prevent feeding movement of the carriage in the event that a cake of ice is not in position upon the slideway 13. This mechanism consists of spaced contacts 127 and 128 adapted to be closed by a bridge 129 carrying a spring pressed plunger 130 in the path of movement of a cake of ice passing from the conveyor 98 to the slideway 13. This plunger also has a keeper member 131 adapted to be engaged by a spring pressed bolt 132 having an angular extension 133, the turned end of which 134 is positioned in the path of movement during the return or backing up movement of this carriage, to receive a cake of ice. By this arrangement, when the switch has once been closed as a result of the

engagement of a cake of ice therewith, it will remain closed, notwithstanding that the end of the cake of ice will pass from engaging relation therewith, and still permit the closing of the circuit to the motor 65; but in the event of the failure of the conveyor mechanism to deliver a cake of ice to the slideway, the circuit will be opened and thus prevent movement of the carriage.

10 The operation of the herein described machine is substantially as follows:—

Assuming that the storage conveyor is properly and fully charged with four hundred pound cakes of ice, (the machine shown 15 in the drawings being designed to handle cakes of this size), that a cake has passed to upon the slideway 13, and that the last piece of ice of the preceding cake, (the lower piece of the last vertical cut), is still adjacent the cutoff mechanism, the deposit of a 20 coin, or check, or the use of a key by the purchaser, and the forcing inwardly of one of the plungers 111—112 will result in the following action of the machine:—

25 The movement of the plunger inwardly will break the circuit at one of the terminals of the mechanism 109 and make the circuit at the other terminals of said mechanism, thus placing these terminals in circuit with 30 the closed terminals of the mechanism 113, and therethrough to the motor 33. This will cause the rotation of the shaft 66 and of the cam 115, the rise 117 on which will, after approximately 180° of movement of 35 the shaft, move the rock lever 114 and actuate the switch member 113 so as to break the circuit through one set of contacts carried thereby and close the other set of contacts carried by said member. This will interrupt 40 the circuit to the motor 33 since the contacts upon the mechanism 113 thus closed are in electrical connection with the contacts upon the mechanism 109 which were opened as a 45 result of the actuation of the plunger by the purchaser.

As the shaft 66 and the cams 31 and 32 are thus turned, the riser 37 of each cam will force the push rods 29 and 30 downwardly, and through the levers 21 and 22, impart 50 oscillatory movement to the bars 16 and 17 carrying the vertical sets of picks or chisels 14 and 15 and the horizontal sets of picks or chisels 25 and 26. This movement of said chisels will merely result in the lower portion 55 of the vertical rows entering between the piece of ice and the fresh cake, so as to ensure the freeing of this piece in the event that it may have frozen to the new cake. The horizontal rows of picks will pass above 60 this piece of ice and do no work.

The continued rotation of the cams 31 and 32 will permit the push bars 29 and 30 to ascend, following the fall of said cams. When they have ascended to the full extent, 65 the vertical rows of picks will be moved to

opposite sides of the slideway 13, thus affording a clear field for the movement of the cake of ice along this slideway.

Substantially simultaneously with this withdrawal of said picks, the rise 125 on the cam 123, which is driven from the shaft 66 at a speed ratio of one to two, will actuate the member 121 so as to close the circuit through the switches 67 and 77 to the motor 65 and thus rotate the lead screw 63, and 75 impart traverse to the carriage 62 through the nut 64.

As the make and break mechanism 67 approaches the first projection 68, the arm 119 will actuate said make and break mechanism 80 by engagement with said projection and so set the mechanism 67 as to open one set of contacts carried thereby and close the other, thus incidently opening the circuit to the switch 77 since this last set of contacts thus closed is in circuit with the set of contacts upon the member 121 opened as a result of the action of the cam 123 thereon. This movement of the carriage will force the piece of ice adjacent the delivery chute 39 90 onto said chute below the chute section 49, the piece of ice sliding along the chute automatically opening the door 41 and entering the chamber 40 where the purchaser by the use of the foot pedal 48 may tilt the 95 bin 42, and thus obtain access to the cake of ice.

The above is the action of the mechanism for one of the cycles of the machine during 100 which the lower piece of ice is delivered by the machine, and will constitute every second cycle in the operation of the machine, the functionings of the machine, however, being varied during one of these cycles when it is necessary to deliver a fresh cake 105 of ice to the slideway 13.

Upon the next actuation of the make and break mechanism 109 by the other plunger 111 or 112, the circuit to the motor 33 will be closed through the switch mechanism 113 110 which, as stated, was set preparatory to this condition during the preceding cycle of operations of the machine. In the meanwhile the delivery of the last piece of ice will have brought the forward end of the next 115 cake 61 within the operative range of both the vertical and horizontal rows of picks, so that during the following 180° of movement of the cams 31 and 32, the sequence of progressively higher risers 35 will cause 120 a succession of jabs by both rows of picks or chisels, causing at the same time cleavage of the cake of ice along a vertical line, and along a horizontal line substantially coincident with the longitudinal center of 125 the cake of ice 61.

When the picks have been forced inwardly to their full extent, the concentric portion 36 of the cams 31 and 32 will maintain the picks in this position. At the same time the 130

striker members 58 upon each cam will raise and pass the cranks 57 and through the links 56 raise the hinged bars 23 and 24 carrying the horizontal rows of picks, so as to tilt this row of picks in a manner to discharge the upper piece of ice upon the upper chute section 49 along which it will descend until it engages the bumper surface 55. During this movement of the cake of ice, the chute 49 will descend from the weight of the ice, the rate of movement of said section being governed by the retard device 53. The cake of ice will slide from the chute 49 to the chute 39, and be delivered in the manner heretofore described. The cams will come to rest while the concentric portion 36 is thus engaged with the push bars 29 and 30.

The stops 94 and 95 will prevent accidental displacement of the lower piece of ice while the upper piece is thus being delivered.

Owing to the fact that the gear 126 has merely one-quarter of a revolution during one-half of the revolution of the shaft 66, the make and break mechanism 121 will not be actuated during this cycle of operations, the carriage having no feeding movement as a result.

These two cycles will be repeated until seven vertical cuts have been made and until the carriage is advanced to bring the cake of ice to a point where the vertical rows of picks will pass the end of the ice adjacent the carriage and be inoperative to cause a vertical cut, but permitting the horizontal rows of picks to divide the last section of ice horizontally and deliver it to the chute section 49.

Upon the last actuation above referred to, the carriage 62 will be closely adjacent the end of the slides 13 toward the cutoff mechanism, the tongs setting and holding the last cut of ice, but being released sufficiently to permit the delivery of the upper piece.

Upon the next actuation of the machine, the carriage will advance until the arm 78 of the reversing switch mechanism 77 engages the abutment 80, the lower piece of ice being moved along the slides a short distance during this movement of the carriage. During this movement the arm 120 carried by the member 67 will be brought to a position where, during the resulting reversed movement of the carriage, it will be caused to pass, without engaging, the various stops 68 to 74 in the inverse order. As the carriage approaches the limit of this reverse movement, it will engage the turned end 134 of the bolt 132, withdrawing this bolt from the keeper 131, and thus permitting movement of the bridge 129 away from the contacts 127 and 128, and interrupting the circuit to the motor 65. Immediately prior to this stoppage of the carriage, the striker

member 108 upon this carriage will oscillate the shaft 106, thus causing the lift member thereon to raise the arm 105, relieving the drum 102 from pressure from the band brake 103, and permitting the belt 96 to move freely under the load of ice thereon until a cake of ice 61 is moved upon the skids 101, along which it may pass to the slideway 13, incidently contacting with the plunger 130 and engaging the contacts 127, 128 and 129, and closing the circuit to the motor 65 since none of the other make and break mechanisms have been disturbed during the interim.

When the circuit has thus been closed, the carriage will continue its reverse or backing up movement until the arm 78 of the mechanism 77 engages the abutment 79 and thus tilts the mercury switch of said mechanism to reverse the motor 65. At the same time the arm 120 will be so actuated as to bring it within the operative range of the projections 68 to 74, and the tongs will be released so as to close upon the cake of ice.

The carriage will then have movement toward the cutoff mechanism, moving the cake of ice along the slideway 13 until the forward end thereof engages the remaining and lower piece of the preceding cake of ice, forcing it upon the chute 39 and bringing a fresh cake of ice with its forward end into the operative position with relation to the cutoff mechanism. Substantially simultaneously with this positioning of parts, the first projection 68 will actuate the make and break mechanism 67 to interrupt the circuit to the motor 65 and thus stop all of the mechanisms in the machine until the delivery of the next piece of ice is required.

As the conveyor belt 96 moves with the ice, the arm 105 will be held by the cake of ice being thus delivered, until this ice has passed from engaging relation with the arm, whereupon the arm will descend and be engaged by the succeeding cake of ice, so that a slight continued movement of the belt or the cake of ice thereon engaging said arm, will reset the band brake and stop further movement of the belt. In releasing the band brake, the lever 104 will be turned slightly in a direction counter to the movement of the belt. The cleats upon the belt will afford that clearance between the cakes of ice desirable not only to prevent succeeding cakes of ice being bonded together, but also to compensate for the taper in the ice itself, while at the same time permitting space for disengagement of said arm from one cake of ice and its engagement with the succeeding cake.

This modified cycle of the operation of the machine will cause a slight delay in the delivery of the piece of ice as a result of the cycle, but since the movement of the car-

riage is but slightly over four feet, and the rate of movement fairly high, this delay will not be appreciable.

The capacity of the conveyor belt 96 may 5 be such as to permit the storage of several tons of ice, and the construction and arrangement of the machine is such as to permit its reliable operation when cutting the several cakes into smaller pieces and delivering them under the conditions described.

As stated heretofore, the projections 68 to 15 74 are spaced at progressively increased distances apart toward the cutoff mechanism to compensate for the taper in the cakes of ice, and these projections may be varied in 20 number and in their spacing to determine the sizes of the pieces of ice into which each cake is cut, and thus compensate for price variation during different seasons, or during different parts of the same season. It will be readily understood that such adjustment will have the effect of varying the spacing between vertical cuts.

The machine may operate without an attendant, it being required, however, from time to time to recharge the conveyor belt with cakes of ice, although the loading switch mechanism will prevent the actuation of the machine when there is no ice to be 30 delivered.

The check or other controlling mechanism may be so constructed as to prevent the deposit of coins, or checks, or the actuation of plungers 111-112 while the loading switch 35 is open. This, however, is no part of the present invention, and is therefore not shown nor described.

It is not my intention to limit the invention to the precise details of construction 40 shown, since such may be varied without departing from the spirit and scope of the invention.

Having described the invention, what I claim as new and desire to have protected 45 by Letters Patent, is:-

1. An ice vending machine embodying therein a cutoff mechanism adapted to intermittently and progressively separate a cake of ice into a plurality of pieces, a feeding 50 mechanism whereby succeeding cakes of ice may be advanced toward and brought into the operative relation to, said cutoff mechanism as required, a storage mechanism adapted to deliver cakes of ice as required 55 in operative relation to said feeding mechanism, delivery means whereby pieces of ice severed by said cutoff mechanism from the cakes of ice are delivered exteriorly of the machine, means whereby the operation of 60 said mechanisms may be controlled from exteriorly of the machine, and an insulated housing inclosing said mechanisms.

2. An ice vending machine embodying 65 therein a cutoff mechanism including a row of vertically extending picks, a row of hori-

zontally extending picks projecting from said vertical row of picks, supports for said picks, means operative upon said supports to move said picks toward and from a cake of ice, a cam operative upon said last named 70 means to control the movements of said supports, means whereby cakes of ice are successively brought into the operative relation to said cutoff mechanism to be separated into a plurality of pieces, delivery means whereby pieces of ice severed by said cutoff mechanism are delivered exteriorly of the machine, means exposed exteriorly of the machine whereby the operation of said cam may be controlled, and an insulating housing 80 inclosing said mechanisms.

3. An ice vending machine embodying therein a cutoff mechanism including two oppositely disposed rows of vertically extending picks, two oppositely disposed rows 85 of horizontally extending picks projecting from said vertical rows of picks respectively, supports for said picks, means operative upon said supports to move said picks toward and from a cake of ice, a plurality of 90 similar cams operative upon said last named means to control the movements of said supports, means whereby cakes of ice are successively brought into the operative relation to said cutoff mechanism to be separated into a plurality of pieces, delivery means whereby pieces of ice severed by said cutoff mechanism are delivered exteriorly of the machine, means exposed exteriorly of the machine whereby the operation of said cams 95 may be controlled, and an insulating housing inclosing said mechanisms.

4. An ice vending machine embodying therein a cutoff mechanism including a row of vertically extending picks, a row of horizontally extending picks projecting from said vertical row of picks, supports for said picks, means operative upon said supports to move said picks toward and from a cake of ice, a cam operative upon said last named 100 means to control the movements of said supports, means whereby cakes of ice are successively brought into the operative relation to said cutoff mechanism to be separated into a plurality of pieces, a delivery chute 105 whereby pieces of ice severed by said cutoff mechanism are delivered exteriorly of the machine, means operative in synchronism with the movement of said cam whereby said horizontal row of picks is tilted to deliver a piece of ice above said picks to said chute, means exposed exteriorly of the machine whereby the operation of said cam 110 may be controlled, and an insulating housing inclosing said mechanisms.

5. An ice vending machine embodying therein a cutoff mechanism including two oppositely disposed rows of vertically extending picks, two oppositely disposed rows 115 of horizontally extending picks projecting 120 from said vertical rows of picks respectively, supports for said picks, means operative upon said supports to move said picks toward and from a cake of ice, a cam operative upon said last named means to control the movements of said supports, means whereby cakes of ice are successively brought into the operative relation to said cutoff mechanism to be separated into a plurality of pieces, delivery means whereby pieces of ice severed by said cutoff mechanism are delivered exteriorly of the machine, means exposed exteriorly of the machine whereby the operation of said cam 125 may be controlled, and an insulating housing inclosing said mechanisms.

- from said vertical rows of picks respectively, supports for said picks, means operative upon said supports to move said picks toward and from a cake of ice, a plurality of 5 similar cams operative upon said last named means to control the movements of said supports, means whereby cakes of ice are successively brought into the operative relation to said cutoff mechanism to be separated into 10 a plurality of pieces, a delivery chute whereby pieces of ice severed by said cutoff mechanism are delivered exteriorly of the machine, means operative in synchronism with the movement of said cams whereby said 15 horizontal rows of picks are tilted to deliver a piece of ice above said picks to said chute, means exposed exteriorly of the machine whereby the operation of said cams may be controlled, and an insulating housing in- 20 closing said mechanisms.
6. An ice vending machine embodying therein a cutoff mechanism including a row of vertically extending picks, a row of horizontally extending picks projecting 25 from said vertical row of picks, supports for said picks, means operative upon said supports to move said picks toward and from a cake of ice, a cam operative upon said last named means to control 30 the movements of said supports, means whereby cakes of ice are successively brought into the operative relation to said cutoff mechanism to be separated into a plurality of pieces, a delivery chute whereby 35 pieces of ice severed by said cutoff mechanism are delivered exteriorly of the machine, the support for said horizontal row of picks being pivoted remotely from said vertical row of picks, a lever adjacent said cam, a 40 link connecting said lever and the free end of the support for said horizontal row of picks, a striker member movable with said cam and adapted to engage said lever, whereby said horizontal row of picks is tilted to 45 deliver a piece of ice above said picks to said chute, means exposed exteriorly of the machine whereby the operation of said cam may be controlled, and an insulating housing inclosing said mechanisms.
- 50 7. An ice vending machine embodying therein a cutoff mechanism including two oppositely disposed rows of vertically extending picks, two oppositely disposed rows of horizontally extending picks projecting 55 from said vertical rows of picks respectively, fixed and said movable supports for said picks, means operative upon said supports to move said picks toward and from a cake of ice, a plurality of similar cams operative 60 upon said last named means to control the movements of said supports, means whereby cakes of ice are successively brought into the operative relation to said cutoff mechanism to be separated into a plurality of 65 pieces, a delivery chute whereby pieces of ice severed by said cutoff mechanism are delivered exteriorly of the machine, the supports for said horizontal rows of picks being pivoted remotely from said vertical rows of picks, levers adjacent said cams, links connecting said levers and the free ends of the supports for said horizontal rows of picks, striker members movable with said cams and adapted to engage said levers, whereby said horizontal rows of picks are tilted to deliver 70 a piece of ice above said picks to said chute, means exposed exteriorly of the machine whereby the operation of said cams may be controlled, and an insulating housing in- 75 closing said mechanisms.
8. An ice vending machine embodying therein a cutoff mechanism including a row of vertically extending picks, a row of horizontally extending picks projecting from said vertical row of picks, supports for said picks, means operative upon said supports to move said picks toward and from a cake of ice, a cam operative upon said last named means to control the movements of said supports, means whereby cakes of ice are successively brought into the operative relation to said cutoff mechanism to be separated into a plurality of pieces, delivery means whereby pieces of ice severed by said cutoff mechanism are delivered exteriorly of the machine, means exposed exteriorly of the machine whereby the operation of said cam may be controlled, an electric motor for actuating said cam, an electrical make and break mechanism actuated by said means 85 exposed exteriorly of the machine, an electrical make and break mechanism actuated in synchronism with said cam, said make and break mechanisms being in circuit with said motor and so set as to permit the first 90 named make and break mechanism to close the circuit to said motor and said other make and break mechanism to open the circuit to said motor after said cam has moved 95 approximately 180°, and an insulating housing 100 inclosing said mechanisms.
9. An ice vending machine embodying therein a cutoff mechanism including a row of vertically extending picks, a row of horizontally extending picks projecting from said vertical row of picks, supports for said picks, means operative upon said supports to move said picks toward and from a cake of ice, a cam, having a sequence of rises of 105 progressively increasing heights and a concentric portion within 180° of the circumference of said cam, and a single rise and fall within the remaining 180° of said circumference, operative upon said last named means to control the movements of said supports, and a spring acting upon said means counter to the action of said cam, means whereby cakes of ice are successively brought 115 into the operative relation to said cutoff mechanism to be separated into a plurality of 120 pieces, a delivery chute whereby pieces of ice severed by said cutoff mechanism are delivered exteriorly of the machine, the supports for said horizontal rows of picks being pivoted remotely from said vertical rows of picks, levers adjacent said cams, links connecting said levers and the free ends of the supports for said horizontal rows of picks, striker members movable with said cams and adapted to engage said levers, whereby said horizontal rows of picks are tilted to deliver 125 a piece of ice above said picks to said chute, means exposed exteriorly of the machine whereby the operation of said cams may be controlled, and an insulating housing in- 130 closing said mechanisms.

of pieces, delivery means whereby pieces of ice severed by said cutoff mechanism are delivered exteriorly of the machine, means exposed exteriorly of the machine whereby the 5 operation of said cam may be controlled, and an insulating housing inclosing said mechanisms.

10. An ice vending machine embodying therein a cutoff mechanism including two 10 oppositely disposed rows of vertically extending picks, two oppositely disposed rows of horizontally extending picks projecting from said vertical rows of picks respectively, supports for said picks, means operative 15 upon said supports to move said picks toward and from a cake of ice, a plurality of similar cams, each having a sequence of rises of progressively increasing heights and a concentric portion within 180° of the circumference of each cam, and a single rise 20 and fall within the remaining 180° of said circumference, operative upon said last named means to control the movements of said supports, springs acting upon said 25 means counter to the action of said cams, means whereby cakes of ice are successively brought into the operative relation to said cutoff mechanism to be separated into a plurality of pieces, delivery means whereby 30 pieces of ice severed by said cutoff mechanism are delivered exteriorly of the machine, means exposed exteriorly of the machine whereby the operation of said cams may be controlled, and an insulating housing inclosing 35 said mechanisms.

11. An ice vending machine embodying therein a cutoff mechanism adapted to intermittently and progressively separate a cake of ice into a plurality of pieces, a feeding mechanism whereby succeeding 40 cakes of ice may be advanced toward and brought into the operative relation to, said cutoff mechanism as required, comprising therein a slideway adapted to receive a cake 45 of ice, a carriage movable along said slideway, whereby a cake of ice may be moved toward said cutoff mechanism, means for imparting movement to said carriage, an electrical motor for actuating said means, 50 co-operating means carried by said carriage, and adjacent said slideway, whereby the circuit to said motor will be automatically interrupted at predetermined intervals, a storage mechanism, means operative by said cutoff 55 mechanism whereby the circuit to said motor will be closed at predetermined intervals, delivery means whereby pieces of ice severed by said cutoff mechanism from the 60 cakes of ice are delivered exteriorly of the machine, means whereby the operation of said mechanisms may be controlled from exteriorly of the machine, and an insulated housing inclosing said mechanisms.

12. An ice vending machine embodying 65 therein a cutoff mechanism adapted to inter-

mittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake of ice, a carriage movable along said slideway, whereby a cake of ice may be moved toward said cutoff mechanism, means for imparting movement to said carriage, an electrical motor for actuating said means, co-operating means carried by said carriage, and adjacent said slideway, whereby the circuit to said motor will be automatically interrupted at predetermined intervals, means operative by said cutoff mechanism whereby the circuit to said motor will be closed at predetermined intervals, a reversing switch upon said carriage and in circuit with said motor, 75 means adjacent opposite ends of said slideway whereby said switch will be actuated to control the direction of movement of the motor and the carriage, a storage mechanism, delivery means whereby pieces of ice severed by said cutoff mechanism from the 80 cakes of ice are delivered exteriorly of the machine, means whereby the operation of said mechanisms may be controlled from exteriorly of the machine, and an insulated 85 housing inclosing said mechanisms.

13. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake 100 of ice, a carriage movable along said slideway, whereby a cake of ice may be moved toward said cutoff mechanism, a lead screw, and a nut upon said carriage for imparting movement thereto, an electrical motor for actuating said lead screw, an oscillatory two-way switch upon said carriage, spaced projections co-operating therewith and positioned along said slideway, whereby the circuit to said motor will be automatically 105 interrupted at predetermined intervals, means operative by said cutoff mechanism whereby the circuit to said motor will be closed at predetermined intervals, a reversing switch upon said carriage and in circuit with said motor, means adjacent opposite ends of said slideway whereby said switch will be actuated to control the direction of movement of the motor and the carriage, a storage mechanism, delivery means whereby pieces of ice severed by said cutoff mechanism from the 110 cakes of ice are delivered exteriorly of the machine, means whereby the operation of said mechanisms may be controlled from exteriorly of the machine, 115 and an insulated housing inclosing said mechanisms.

14. An ice vending machine embodying 120 therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake 125 of ice, a carriage movable along said slideway, whereby a cake of ice may be moved toward said cutoff mechanism, a lead screw, and a nut upon said carriage for imparting movement thereto, an electrical motor for actuating said lead screw, an oscillatory two-way switch upon said carriage, spaced projections co-operating therewith and positioned along said slideway, whereby the circuit to said motor will be automatically 130 interrupted at predetermined intervals, means operative by said cutoff mechanism whereby the circuit to said motor will be closed at predetermined intervals, a reversing switch upon said carriage and in circuit with said motor, means adjacent opposite ends of said slideway whereby said switch will be actuated to control the direction of movement of the motor and the carriage, a storage mechanism, delivery means whereby pieces of ice severed by said cutoff mechanism from the cakes of ice are delivered exteriorly of the machine, means whereby the operation of said mechanisms may be controlled from exteriorly of the machine, 135 and an insulated housing inclosing said mechanisms.

and an insulated housing inclosing said mechanisms.

14. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake of ice, a carriage movable along said slideway, whereby a cake of ice may be moved toward said cutoff mechanism, tongs upon said carriage adapted to engage a cake of ice upon said slideway, means adjacent opposite ends of the slideway for automatically opening and closing said tongs, means for imparting movement to said carriage, an electrical motor for actuating said means, co-operating means carried by said carriage, and adjacent said slideway, whereby the circuit to said motor will be automatically interrupted at predetermined intervals, means operative by said cutoff mechanism whereby the circuit to said motor will be closed at predetermined intervals, a reversing switch upon said carriage and in circuit with said motor, means adjacent opposite ends of said slideway whereby said switch will be actuated to control the direction of movement of the motor and the carriage, a storage mechanism, delivery means whereby pieces of ice severed by said cutoff mechanism from the cakes of ice are delivered exteriorly of the machine, means whereby the operation of said mechanisms may be controlled from exteriorly of the machine, and an insulated housing inclosing said mechanisms.

15. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake of ice, a carriage movable along said slideway, whereby a cake of ice may be moved toward said cutoff mechanism, means for imparting movement to said carriage, an electrical motor for actuating said means, co-operating means carried by said carriage, and adjacent said slideway, whereby the circuit to said motor will be automatically interrupted at predetermined intervals, means operative by said cutoff mechanism whereby the circuit to said motor will be closed at predetermined intervals, an electrical loading switch mechanism adjacent said slideway and acted upon by a cake of ice to close same, said mechanism being in circuit with said motor, means whereby said mechanism may be maintained in a closed position while the carriage is

having movement toward the cutoff mechanism, but is permitted to open toward the limit of the movement of said carriage away from said cutoff mechanism, a reversing switch upon said carriage and in circuit with said motor, means adjacent opposite ends of said slideway whereby said switch will be actuated to control the direction of movement of the motor and the carriage, a storage mechanism, delivery means whereby pieces of ice severed by said cutoff mechanism from the cakes of ice are delivered exteriorly of the machine, means whereby the operation of said mechanisms may be controlled from exteriorly of the machine, and an insulated housing inclosing said mechanisms.

16. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive a cake of ice, a carriage movable along said slideway, whereby a cake of ice may be moved toward said cutoff mechanism, means for imparting movement to said carriage, an electrical motor for actuating said means, co-operating means carried by said carriage, and adjacent said slideway, whereby the circuit to said motor will be automatically interrupted at predetermined intervals, a two-way tiltable reversing switch upon said carriage in circuit with said motor, abutments adjacent opposite ends of said slideway operative upon said reversing switch, a two-way tiltable switch mechanism adjacent said cutoff mechanism, means operative by said cutoff mechanism and acting upon said last named switch mechanism, whereby the circuit to said motor will be closed at predetermined intervals, a storage mechanism, delivery means whereby pieces of ice severed by said cutoff mechanism from the cakes of ice are delivered exteriorly of the machine, means whereby the operation of said mechanisms may be controlled from exteriorly of the machine, and an insulated housing inclosing said mechanisms.

17. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising therein a slideway adapted to receive cakes of ice, a carriage movable along said slideway, whereby cakes of ice may be moved toward said cutoff mechanism, means for imparting movement to said carriage, an electrical motor

for actuating said means, co-operating means carried by said carriage, and adjacent said slideway, whereby the circuit to said motor will be automatically interrupted at predetermined intervals, means operative by said cutoff mechanism whereby the circuit to said motor will be closed at predetermined intervals, a reversing switch upon said carriage and in circuit with said motor, means adjacent opposite ends of said slideway whereby said switch will be actuated to control the direction of movement of the motor and the carriage, an inclined conveyor mechanism adapted to receive a plurality of cakes of ice, means whereby said conveyor mechanism will operate from the action of the load of ice thereon to deliver ice to said slideway, means normally preventing the operation of said conveyor mechanism, means upon and movable with said carriage, and operative upon said means preventing operation of the conveyor mechanism to make it inoperative when the carriage is in a position to permit a cake of ice to pass to upon said slideway, a member carried by said means preventing operation of the conveyor mechanism adapted to be engaged by the ice upon said conveyor, to make said means preventing operation of the conveyor mechanism operative after a cake of ice has passed to said slideway, delivery means whereby pieces of ice severed by said cutoff mechanism from the cakes of ice are delivered exteriorly of the machine, means whereby the operation of said mechanisms may be controlled from exteriorly of the machine, and an insulated housing inclosing said mechanisms.

18. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, comprising a slideway adapted to receive a cake of ice, a carriage movable along said slideway, whereby a cake of ice may be moved toward said cutoff mechanism, means for imparting movement to said carriage, an electrical motor for actuating said means, co-operating means carried by said carriage, and adjacent said slideway, whereby the circuit to said motor will be automatically interrupted at predetermined intervals, means operative by said cutoff mechanism whereby the circuit to said motor will be closed at predetermined intervals, a reversing switch upon said carriage and in circuit with said motor, means adjacent opposite ends of said slideway whereby said switch will be actuated to control the direction of movement of the motor and the carriage, an inclined conveyor mechanism adapted to receive a plurality of cakes of ice, rollers about which said conveyor mechanism passes, a brake drum operative upon one of said rollers, a brake band co-operating with said drum, an oscillatory lever acting upon said brake band, an arm mounted by a horizontal pivot upon said lever and projecting in the path of movement of ice upon said conveyor, whereby the ice upon said conveyor will act to normally set said brake band, means operative to move said arm out of engaging relation with a cake of ice, a striker member upon and movable with the carriage, whereby said arm will, as a result of the movement of said carriage, be disengaged from one cake of ice and positioned to engage the succeeding cake of ice, delivery means whereby pieces of ice severed by said cutoff mechanism from the cakes of ice are delivered exteriorly of the machine, means whereby the operation of said mechanisms may be controlled from exteriorly of the machine, and an insulated housing inclosing said mechanisms.

19. An ice vending machine embodying therein a cutoff mechanism including two oppositely disposed rows of vertically extending picks, two oppositely disposed rows of horizontally extending picks projecting from said vertical rows of picks respectively, movable supports carrying said picks, fixed supports adjacent said movable supports, toggle levers connecting said supports, push bars operative upon said levers, restoring springs operative upon said levers, a plurality of cams operative upon said push rods to control the movements of said supports, means whereby cakes of ice are successively brought into the operative relation to said cutoff mechanism to be separated into a plurality of pieces, a delivery chute whereby pieces of ice severed by said cutoff mechanism are delivered exteriorly of the machine, means operative in synchronism with the movement of said cams whereby said horizontal rows of picks are tilted to deliver a piece of ice above said picks to said chute, means exposed exteriorly of the machine whereby the operation of said cams may be controlled, and an insulating housing inclosing said mechanisms.

20. An ice vending machine embodying therein a cutoff mechanism adapted to intermittently and progressively separate a cake of ice into a plurality of pieces, a feeding mechanism whereby succeeding cakes of ice may be advanced toward and brought into the operative relation to, said cutoff mechanism as required, a storage mechanism adapted to deliver cakes of ice as required in operative relation to said feeding mechanism, a chute leading from adjacent said cutoff mechanism, a tiltable bin adjacent the opposite end of said chute, means exposed exteriorly of the machine whereby said bin may be

- opened to permit a purchaser to receive a piece of ice therefrom, means whereby the operation of said mechanisms may be controlled from exteriorly of the machine, and 5 an insulated housing inclosing said mechanisms.
21. An ice vending machine embodying therein a cutoff mechanism adapted to intermittently and progressively separate a cake 10 of ice into a plurality of pieces, a feeding mechanism whereby succeeding cakes of ice may be advanced toward and brought into the operative relation to, said cutoff mechanism as required, a storage mechanism 15 adapted to deliver cakes of ice as required in operative relation to said feeding mechanism, a chute leading from adjacent said cutoff mechanism, a second chute pivoted above and spaced away from said first 20 named chute, a stop adjacent the end of said last named chute, a retard device operative upon said upper chute, said upper chute being adapted to descend from the weight of a piece of ice so as to cause such ice to pass 25 upon said first named chute, a tiltable bin adjacent the opposite end of said chute, means exposed exteriorly of the machine whereby said bin may be opened to permit a purchaser to receive a piece of ice therefrom, 30 means whereby the operation of said mechanisms may be controlled from exteriorly of the machine, and an insulated housing inclosing said mechanisms.
22. In an ice vending machine, the combination with means for supporting a large 35 ice cake, of means for delivering a smaller section of ice cake, and means actuated in conjunction with said delivery means for severing a smaller section from the large ice cake. 40
23. In an ice vending machine, the combination with means for supporting a large ice cake, of means for delivering a smaller section of ice cake, and means actuated in conjunction with said delivery means for 45 successively severing smaller sections from the large cake.
24. In an ice vending machine, the combination with means for storing a series of large ice cakes, of means for intermittently 50 advancing said series, means operating in the intervals between successive advancements for intermittently advancing one of said cakes in a direction transverse to the advancement of the series, and means for severing and delivering sections from the latter cake in its successive positions of advancement. 55

In witness whereof I have hereunto affixed my signature this 12th day of June, 60
1924

GEORGE L. BENNETT.
